(57) **CLAIM**

The ornamental design for a coordinate input device, as shown and described.

DESCRIPTION

FIG. 1 is a front top right isometric view of a coordinate input device according to my new design;
FIG. 2 is a rear bottom left isometric view thereof;
FIG. 3 is a top plan view thereof;
FIG. 4 is a bottom plan view thereof;
FIG. 5 is a front elevation view thereof;
FIG. 6 is a rear elevation view thereof;
FIG. 7 is a left side elevation view thereof, wherein the right side elevation view is symmetrical to the left side elevation view;
FIG. 8 is a rear bottom left isometric view thereof, showing the coordinate input device in a second position; and,
FIG. 9 is a top plan view thereof.

The broken lines show portions of the coordinate input device which form no part of the claimed design. FIG. 9 depicts one representative location for a coordinate input instrument, shown in broken line, forming no part of the claimed design.
